UNITED STATES PATENT OFFICE.

FRANK M. LOKOMETZKI, OF MILWAUKEE, WISCONSIN.

CLOTHESPIN.

1,413,341.

Specification of Letters Patent. Patented Apr. 18, 1922.

Application filed May 18, 1921. Serial No. 470,551.

To all whom it may concern:

Be it known that I, FRANK M. LOKOMETZKI, a citizen of the United States, residing at Milwaukee, in the county of Milwaukee, State of Wisconsin, have invented certain new and useful Improvements in Clothespins; and I do hereby declare the following to be a full, clear, and exact description of the invention, such as will enable others skilled in the art to which it appertains to make and use the same.

This invention relates to new and useful improvements in clothes pins, and particularly to wire clothes pins.

15 One object of the invention is to provide a clothes pin, formed from a single length of suitable stiff wire which will firmly grip the clothes and line and which will readily move with the clothes and line, as the wind 20 blows them, without danger of becoming disengaged from the clothes and line.

Another object is to provide a clothes pin of this character wherein certain helix turns of the twisted portions of the legs are out of 25 contact with each other, to permit flexing of approximately the entire length of the legs.

Another object is to provide a clothes pin having a pair of twisted flexible legs each of 30 which is formed with an outwardly bowed portion, portions of the twist being loose to permit flexibility of the legs to cause the bowed portions to firmly embrace the clothes and line.

35 Other objects and advantages will be apparent from the following description when taken in connection with the accompanying drawing.

In the drawing:

40 Figure 1 is a side elevation of a clothes pin made in accordance with the invention, the same being shown engaged with a garment and a line, the latter being in section.

Figure 2 is a front elevation of the pin.

45 As seen in the drawing the pin is formed from a single length of wire. This wire is preferably stiff, but of the required flexibility to readily open when being applied to or removed from a line. The wire is bent at 50 its intermediate point to form the legs 10, and said legs are twisted together, as shown.

Beyond the twisted portions of the legs there are formed the outwardly and oppositely bowed portions 11 which are adapted to embrace the clothes and line. Below the bowed portion the legs are extended in gradual divergent relation with outwardly disposed terminal eyes. These divergent portions of the legs form a V-shaped entrance or throat 12, into which the clothes and line are passed for position between the bowed portions. The closed end of the pin is formed into a large eye 13, which serves as a fingerpiece, for handling the pin when applying the same to or removing it from a line.

Attention is particularly called to the fact that only the uppermost of the helix turns of the twisted portions of the legs contact, the lower turns being out of contact, and slightly spaced apart, with the result that 70 when the line is forced between the lower ends of the legs, the said legs will flex bodily toward and away from each other throughout their entire lengths. Thus the entire flexibility of the legs is brought into play, 75 with the result that the pin will readily permit application to or removal from the line, and will retain their grip on the clothes and line under great strains, especially in high winds, when the clothes are tossed back and forth. Furthermore, should the clothes become frozen, the flexibility of the legs, and the particular arrangement thereof, will permit the pin being easily and quickly detached.

85 What is claimed is:

A clothes pin formed from a single length of wire and including a pair of parallel legs, a circular bight portion, a twisted portion between the bight portion and the legs, and 90 opposite angularly bowed portions between the twisted portion and the legs, the turns of the twisted portion being out of contact with each other, whereby the wire is capable of complete flexing movement from the 95 bight portion to the outer ends of the legs.

In testimony whereof, I affix my signature, in the presence of two witnesses.

FRANK M. LOKOMETZKI.
